UNITED STATES PATENT OFFICE.

ROBERT G. CLYNE, OF ALTON, ILLINOIS.

SHOT-RECEPTACLE.

1,160,974.

Specification of Letters Patent. Patented Nov. 16, 1915.

Application filed May 20, 1914. Serial No. 839,693.

To all whom it may concern:

Be it known that I, ROBERT G. CLYNE, a subject of the King of Great Britain, residing at Alton, in the county of Madison and State of Illinois, have invented certain new and useful Improvements in Shot-Receptacles, of which the following is a specification.

My invention relates to improvements in shot receptacles, the improved receptacle or container being particularly designed and adapted for the safe and convenient putting up, shipment, and use of air rifle shot for air rifles.

The improved receptacle or container is adapted not only for use as an original package by the manufacturer of such air rifle shot but is designed for use by the merchant or retailer in storing and handling as well as for use by the users in conveniently carrying and dispensing such shot in convenient quantities as needed for use in loading or filling the air rifle.

The primary object of the invention is to provide a generally improved receptacle for the purposes mentioned which will be exceedingly simple in construction, cheap of manufacture, and efficient in use.

With the above mentioned, and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification, Figure 1, is a side elevation of the improved shot receptacle. Fig. 2, an end view of the cap or delivery end thereof, the rotatably mounted cap being in its open position for the convenient delivery of a single shot. Fig. 3, a similar view, the cap being shown in a further open position for the convenient delivery of two or more shot. Fig. 4, a central longitudinal sectional view of the same delivery cap being in its full open position for the delivery of a supply of shot as in filling the air rifle magazine. Fig. 5, an end view of the cap or delivery end of the same. Fig. 6, a similar view of a slightly modified form. Fig. 7, a longitudinal sectional view of a further modified form of delivery cap. Fig. 8, an end view of the same in a partially open position. Fig. 9, an end view of the inner cap detached.

Similar numerals of reference designate like parts throughout all the figures of the drawings.

The improved shot receptacle or container comprises a tubular body or shell 1, preferably of paper similar to that employed with an ordinary paper shot shell and of sufficient strength to withstand the weight of such material as air rifle shot or pellets.

The paper tube or shell 1, is preferably slightly expanded near one end as at 1^a, to form an inner annular seat 1^b, for a circular or disk shaped bottom 2, which member 2, may likewise be formed of paper or card board of sufficient thickness and strength to withstand the weight of the interior contents, and as a convenient means for securing said disk 2, the adjacent end of the tubular body or shell 1, may be crimped inwardly as at 1^c, to rest against the bottom 2, and securely fasten the same as shown in Fig. 4 of the drawings.

The improved delivery top or cap for the improved receptacle comprises a double-walled or two-part cap consisting in an inner flanged cap 3, and a similarly shaped or flanged outer cap 4.

As a means of securing or clamping the caps 3, and 4, upon the end of the tubular body or shell 1, the outer periphery of the inner cap 3, is formed slightly larger in diameter than the inside diameter of the shell 1, and is provided with an inwardly beveled or flanged portion 3^a, so that when the inner cap 3, is forced into the open end of the body or shell 1, said end will be slightly expanded as at 1^d, forming a correspondingly beveled or inclined shoulder 1^e, surrounding the inner cap 3, and the inclined or flanged portions 3^a, and as a means of rotatably mounting the outer cap 4, upon the inner cap 3, as well as arranging the same in coöperative clamping relation to the expanded or shoulder portion 1^e, of the shell, said outer cap is provided with an inwardly extending or flanged portion 4^a, said outer cap being so attached as to permit of its circumferential movement or rotation through the medium of the milled or knurled rim portion shown most clearly in Fig. 1 of the drawings.

As a means for conveniently delivering any desired quantity of shot as well as providing for the interlocking of the outer cap 4, in its closed as well as extreme open position, the inner and outer caps 3, and 4, re-

spectively, are provided with curved delivery slot openings 3^b, and 4^b, respectively, said openings being of corresponding dimensions and being adapted to register with each other when the outer cap is in its fully opened position as shown in Fig. 5 of the drawings, said inner and outer caps being also provided with oppositely arranged inset or depressed portions 3^c, and 4^c, respectively, corresponding in dimensions to the delivery openings 3^b, and 4^b, said inset portions being adapted to register and interlock with each other when the outer cap is fully open as shown in Figs. 4 and 5 of the drawings and said inset or depressed portion 4^c, in the outer cap being adapted to register and interlock with the correspondingly formed delivery slot opening 3^b, in the inner cap when the outer cap is moved to its fully closed position. If desired, however, the curved inset or depressed portions 3^c, and 4^c, need not necessarily correspond in width to the delivery slots 3^b, and 4^b, but may simply correspond in length thereto and be of narrow construction as illustrated in Fig. 6 of the drawings.

In the form shown in Figs. 7, 8 and 9 of the drawings the curved interlocking depressed portions 3^c, and 4^c, are eliminated, the outer cap being adapted to be held in its respective positions by mere frictional contact with the expanded end 1^a, of the tubular body, and as a means of further securing the inner cap the inwardly extending flanged portion 3^a, thereof may be provided with a series or plurality of outwardly extending struck-out anchor projections 3^d, as shown most clearly in Fig. 9 of the drawings, said anchor projections being adapted to extend into the adjacent end of the tubular shell as shown in Fig. 7 of the drawings.

From the foregoing description, taken in connection with the accompanying drawings, the operation and advantages of my invention will be readily understood.

Copies of this patent may be obtained for five cents each, by addressing the "Commissioner of Patents, Washington, D. C."

Having thus described some of the embodiments of my invention, what I claim and desire to secure by Letters Patent, is,—

1. In a slot receptacle, a tubular shaped paper body, and inwardly extending flanged caps taking over the inner and outer marginal edges thereof and provided with similarly shaped delivery openings, said outer flanged cap being rotatably mounted and having an inset portion adapted to ride upon said inner cap and to fit within the delivery opening thereof when moved to its closed position.

2. A shot receptacle, comprising a shell, a disk member crimped therein, and inner and outer caps provided with similarly formed inwardly extending flanged portions taking over the opposite end of said paper shell and interlocking therewith, said caps having similarly shaped delivery slot openings, and said outer cap being rotatably mounted and provided with an inset portion adapted to snap into engagement with the delivery opening in said inner cap when said outer cap has been moved to its closed position.

3. In a shot receptacle, a cylindrical shell, a rimmed cap fitted within the end thereof, a second cap provided with a similarly shaped rim taking over the marginal edges of said cylindrical shell and about said rimmed portion of said first mentioned cap and rotatably mounted thereon, said caps being provided with curved delivery slot openings adapted to be thrown into and out of registry with each other and also provided with means for securing the rimmed portions thereof in engagement with said shell.

In testimony whereof I have affixed my signature in presence of two witnesses.

ROBERT G. CLYNE.
